UNITED STATES PATENT OFFICE

HORACE F. GRUMAN, OF ST. LOUIS, MISSOURI, ASSIGNOR TO LEWIS INVISIBLE STITCH MACHINE COMPANY, OF ST. LOUIS, MISSOURI, A CORPORATION OF MAINE

COMBINED SEAMING AND PINKING MACHINE

Application filed March 13, 1931. Serial No. 522,312.

This invention relates to new and useful improvements in sewing machines especially adapted for performing a seaming and a pinking or trimming operation, and embodies certain improvements on my co-pending application Serial No. 473,404, filed August 6, 1930 issued December 20, 1932, as Patent 1,891,308.

Among the several objects of my invention 10 are to provide a pinking means in which the movable blade is supported by a lever which is positively actuated by a rotary cam which is driven by a reducing speed gear coupling from the main shaft whereby the movable 15 blade will be given an effective cutting stroke once only during several reciprocations of the needle; to provide means for quickly rendering the movable blade ineffective or effective and thereby render the machine useful for 20 seaming purposes either with or without the pinking mechanism; to provide means for yieldingly retaining the ledger blade in cooperative cutting relation with the vertically reciprocable blade; to provide a vertically adjustable cam finger on the blade-carrying 25 lever for cooperation with the ledger blade to insure the latter being properly positioned with respect to the ledger blade when the lever is returned from ineffective to effective 30 position, and to provide such a pinking mechanism which consists of but few parts which are adapted to be readily attached to a standard sewing machine.

With these and other objects in view which 35 will more fully appear, the nature of the invention will be more clearly understood by following the description, the appended claims, and the several views illustrated in 40 the accompanying drawings.

In the drawings:—

Figure 1 is a front elevation of a sewing machine constructed in accordance with my invention,

Figure 2 is a partial rear elevation thereof, Figure 3 is a top plan view of the overhanging arm,

Figure 4 is a partial longitudinal vertical sectional view through the overhanging arm 50 and associated parts,

Figure 5 is a horizontal sectional view taken on the line 5—5 of Figure 1,

Figure 6 is a vertical sectional view taken on the line 6—6 of Figure 1,

Figure 7 is a similar view but taken on the line 7—7 of Figure 1,

Figure 8 is a plan view of the throat plate, feed dog, needle opening, ledger blade, movable blade, and adjustable spring connected to the ledger blade,

Figure 9 is an enlarged diagrammatic view showing the normal relation between the walls of the movable blade and the cutting edges of the ledger blade, the movable blade being in its uppermost position.

Figure 10 is a similar view but showing the relative positions of the blades when the movable blade is in its lowermost position,

Figure 11 is a perspective view of the movable blade and the end of the lever to which it is connected,

Figure 12 is a view more or less diagrammatically showing the overlapping relation of the movable trimmer blade during the pinking operation,

Figure 13 is an enlarged vertical sectional view showing the normal cutting relation between the ledger blade and the movable blade, and

Figure 14 is a similar view but showing the relation of the parts when the movable blade-carrying lever is in its elevated or ineffective position.

Like reference numerals designate corresponding parts throughout the several figures of the drawings.

Referring to the accompanying drawings, my invention has been applied to a sewing machine of the flat bed type which includes a work support 5, a standard 6, an overhanging arm 7, and a needle head 8. Journaled in the overhanging arm is a rotary shaft 9 which is operatively connected by any suitable mechanism to a needle 10 which is mounted in the needle head 8 for vertical reciprocations. Mounted on the work support directly below the needle 10 is a throat plate 11 having feed slots 12 and a needle opening 13 formed therein. Also mounted

- on the needle head 8 is a presser foot 14 which is disposed directly above the feed slots 12 and the needle opening 13. Cooperating with the presser foot 14 below the 5 throat plate 11 for feeding the work rearwardly is a feed dog 15, and cooperating with the needle below the work plate is a rotary hook 16 or any other suitable complementary stitch forming mechanism.
- 10 Fixed to the rotary shaft 9 at a point intermediate the standard 6 and the needle head 8, is a driving gear 17 which is in constant mesh with a driven gear 18 fixed to a countershaft 19 journaled in a housing 20 which is detachably connected to the overhanging arm 7 by screws 21, the housing together with the countershaft and driven gear 18 being thus suspended from the overhanging arm and being located intermediate 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 - mer blade 48. The opening 63 includes two converging cutting edges 64, 64 of an angle slightly more than the angle of the cutting walls 50, 50 of the movable cutting blade. 5 The extensions 53, 53 of the movable cutting blade extend downwardly into the opening 63 of the ledger blade and normally bear against the ends of the cutting edges 64, 64 at points remote from the apex or toe portion 65 of the opening 63. The ledger blade 62 is supported on the throat plate 11 for movements in a line extending in a plane at right angles to the line of feed through the medium of guide plates 66, 66 which are adjustably fixed to the throat plate 11 so as to permit the ledger blade 62 to be adjusted with nicety relative to the movable cutting blade 48. A coil spring 67 has one end connected to a post 68 fixed to the ledger blade 62, the other end of said spring being connected to a plate 69 which is connected to the under side of the work support 5 through the medium of a clamping screw 70 which passes through a slot 71 formed in said plate. Thus 20 by means of the slot 71 the plate 69 may be adjusted toward and from the throat plate 11 and thereby vary the tension of the spring 67. This spring functions to maintain the cutting edges 64, 64 of the ledger blade 62 in contact with the walls 50, 50 and the cutting edges 54, 54 of the movable blade, thereby insuring a clean shearing cutting action to be made. Thus when the movable blade 48 is moved downwardly the ledger blade 62, 25 by reason of the difference in angular relationship of the cutting walls 50, 50 relative to the cutting edges 64, 64 will be moved toward the needle and against the tension of the spring 67, and when the movable blade 48 is elevated the spring 67 will return the ledger blade 62 to its normal position, the return movement being limited by the guide extensions 53 engaging the cutting edges 64 of the ledger blade. 30
- 45 The movable cutting blade 48 is located on the right hand side of the presser foot 14, and disposed in front of the cutting element is an edge guide 72 for the fabrics to be trimmed or seamed, or both. This guide is adjustably mounted on an arm 73 which is fulcrumed to swing about a pivot screw 74 secured to the work support 5. Thus by adjusting the guide 72 longitudinally of the arm 73, the depth of the pinks may be adjusted, or if the cutting mechanism is thrown out of operation, the guide may be swung to an ineffective edge guiding position. 50
- It will be observed that the ledger blade 62 is urged laterally by the spring 67 toward the pivots 27 of the lever 25, and therefore when the lever is swung upwardly to its ineffective cutting position as shown by dotted lines in Figure 1, the movable blade 48 will be lifted clear of the ledger blade and the opening in the latter will be out of registry with the movable blade as shown in Figure 14. Consequently I have provided means for returning the ledger blade to its normal operating position simultaneously with the return movement of the blade-carrying lever. 55 To this end, I have provided the downturned end portion 46 of the lever 25 with a vertical groove 75 and mounted in said groove for vertical adjustments is the upper end of a cam finger 76, the upper end being adjustably attached to the downturned end portion 46 of the lever 25 by a slot and screw connection 77. A cam 78 which is integral with the finger and extends laterally toward the guide extensions 53, is provided with a high point which is located in a horizontal plane containing the lower ends of the extensions 53, the lower end of the cam extending downwardly below said horizontal plane. A stop 79 fixed to the work support 5, limits the lateral movement of the ledger blade under the influence of the spring 67 when the lever 25 is moved upwardly to its ineffective cutting position. The right hand edge of the ledger blade is provided with a recess 80 having a shoulder 81 at its inner end. 60
- Assuming the movable blade 48 is elevated to its ineffective cutting position as shown in Figure 14, the cam finger 76 is correspondingly elevated so that both the blade and the finger are spaced above the ledger blade 62 which has been moved laterally by the spring 67 and bears against the stop 79. 65
- When it is desired to return the movable blade 48 to effective cutting position, the lever 25 is moved downwardly by the finger lever 35 and against the tension of the return spring 34. The lower edge of the cam 78 engages the shoulder 81 and moves the ledger blade 62 against the tension of the spring 67 until the opening in the ledger blade registers with the movable blade 48, and immediately thereafter the extensions 53, 53 of the movable blade are lowered into the opening of the ledger blade and the cam 78 is lowered below the ledger blade to the positions shown in full lines in Figure 13. This action frees the ledger blade from the cam and permits the spring 67 to function and maintain the cutting edges of the ledger blade in yielding contact with the movable cutter 48. In the Figure 13 full line positions, the movable blade 48 is at the upper end of its effective cutting stroke, and the lower end of its reciprocating stroke and the lower end of the reciprocating stroke of the cam, are shown in dotted lines in said figure. Thus the cam 78 reciprocates entirely below the ledger blade during cutting operations and the cam therefore has no effect on the blade during these cutting operations. 70
- In operation, two pieces of fabric A are arranged in superposed relation and fed past the stitch forming mechanism and the trimming mechanism by the feed dog 15. The 75

line of straightaway stitches S is thus formed and these stitches join the two pieces of fabric. By reason of the gear coupling 17, 18 being of a 1-to-3 ratio, the lever 25 is positively moved downwardly once during every three reciprocations of the needle, that is, the movable cutter 48 is moved downwardly simultaneously with the downward movement of the needle and elevated by the spring 34 during the upward stroke of said needle, the needle then making two additional reciprocations while the movable cutting element 48 is at rest. The length of the cutting edges 64, 64 is considerably greater than the length 15 of the edges of a resultant pink and consequently the movable trimmer blade 48 during its cutting operations necessarily overlaps the previously formed pink α as shown in Figure 12, thereby insuring a clear cut apex. 20 From the foregoing, it will be readily understood that when it is desired to employ this machine for seaming operations only, the movable cutter element 48 may be swung upwardly and retained in its inoperative position.

It is of course to be understood that the details of structure and arrangements of parts may be variously changed and modified without departing from the spirit and scope of 30 my invention.

I claim:

1. In a combined seaming and trimming machine, the combination with a rotary shaft, of a stitch forming mechanism including a 35 vertically reciprocable needle operated by said shaft, and a trimmer mechanism including a ledger blade and a vertically reciprocable blade cooperating therewith, a vertically movable pivoted frame carrying the 40 movable blade, driving connections including a cam rotated by the main shaft and having wiping contact with said frame intermediate the pivotal mounting of the frame and the reciprocable blade for vertically 45 moving the latter in one direction and enabling bodily removal of the frame without dismounting any of said driving connections, and a spring for maintaining the frame in operative engagement with said cam.

50 2. In a combined seaming and trimming machine, the combination with a rotary shaft, of a stitch forming mechanism including a vertically reciprocable needle operated by said shaft, and a trimmer mechanism including a ledger blade and a vertically reciprocable blade cooperating therewith, a vertically movable pivoted frame carrying the 55 movable blade, driving connections including a cam rotated by the main shaft and having 60 wiping contact with said frame intermediate the pivotal mounting of the frame and the reciprocable blade for positively moving the latter downwardly into effective cutting relation with the ledger blade and enabling bodily removal of the frame without dismount-

ing any of said driving connections, and a spring for maintaining the frame in operative engagement with said cam.

3. In a combined seaming and trimming machine, the combination with a main frame 70 including a work support, a standard on the work support, and an overhanging arm supported on the standard, of a stitch forming mechanism including a vertically reciprocable needle mounted on the overhanging arm, a rotary shaft journaled in the overhanging arm and having operative connections with said needle, and a trimming mechanism including a ledger blade mounted on the work support and a cooperating movable blade, a countershaft located between the work support and the rotary shaft and supported by the overhanging arm, a gear coupling between the rotary shaft and the countershaft, and a lever carrying the movable blade disposed between the countershaft and the work support and having one end thereof pivotally mounted to swing about a horizontal axis, and a cam fixed to the countershaft and operatively engaging said lever for positively 75 swinging the latter.

4. In a combined seaming and trimming machine, the combination with a main frame including a work support, a standard on the work support, and an overhanging arm supported on the standard, of a stitch forming mechanism including a vertically reciprocable needle mounted on the overhanging arm, a rotary shaft journaled in the overhanging arm and having operative connections with said needle, and a trimming mechanism including a ledger blade mounted on the work support and a cooperating movable blade, a countershaft located between the work support and the rotary shaft and supported by the overhanging arm, a gear coupling between the rotary shaft and the countershaft, and a lever carrying the movable blade disposed between the countershaft and the work support and having one end thereof pivotally mounted to swing about a horizontal axis, a cam fixed to the countershaft and operatively engaging said lever for positively 80 swinging the latter, and a spring for maintaining the lever in operative engagement with said cam.

5. In a combined seaming and trimming machine, the combination with a rotary shaft, of a stitch forming mechanism including a vertically reciprocable needle operated by said shaft, and a trimmer mechanism including a ledger blade and a vertically reciprocable movable blade cooperating therewith, a cam rotated by the main shaft, a lever pivoted on a horizontal axis and carrying the movable blade, and a hand lever fulcrumed on the blade-carrying lever and provided with a roller for engaging said cam, said hand lever being rockable to move the roller into 125 and out of operative relation with the cam.

6. In a combined seaming and trimming machine, the combination with a rotary shaft, of a stitch forming mechanism including a vertically reciprocable needle operated by said shaft, and a trimmer mechanism including a ledger blade and a vertically reciprocable movable blade cooperating therewith, a cam rotated by the main shaft, a lever pivoted on a horizontal axis and carrying the movable blade, a hand lever fulcrumed on the blade-carrying lever and provided with a roller for engaging said cam, said hand lever being rockable to move the roller into and out of operative relation with the cam, and means to limit the operative and inoperative rocking movements of said hand lever.

7. In a combined seaming and trimming machine, the combination with a rotary shaft, of a stitch forming mechanism including a vertically reciprocable needle operated by said shaft, and a trimmer mechanism including a ledger blade and a vertically reciprocable movable blade cooperating therewith, a cam rotated by the main shaft, a lever pivoted on a horizontal axis and carrying the movable blade, a hand lever fulcrumed on the blade-carrying lever and provided with a roller for engaging said cam, said hand lever being rockable to move the roller into and out of operative relation with the cam, means to limit the operative and inoperative rocking movements of said hand lever, and a spring mounted on the blade-supporting lever and cooperating with the roller-supporting lever to retain the latter in either its operative or inoperative position.

8. In a combined seaming and pinking machine, the combination of a stitch forming mechanism including a vertically reciprocatory needle, and a trimming mechanism including a horizontally disposed ledger blade having an opening forming converging cutting edges; a vertically reciprocable movable blade having converging cutting walls normally cooperating with the cutting edges of the ledger blade; means for reciprocating the movable blade including a support for the blade; means for elevating the support to thereby render the movable blade ineffective; means for supporting the ledger blade for lateral movements, a spring connected to the ledger blade for maintaining the latter in yieldable engagement with the movable blade during cutting operations and for moving the ledger blade out of registry with the movable blade when the latter is in its elevated and ineffective position; and means controlled by the movable blade support during the return movement thereof for automatically returning the ledger blade to its normal position.

9. In a combined seaming and pinking machine, the combination of a stitch forming mechanism including a vertically reciprocatory needle, and a trimming mecha-

nism including a horizontally disposed ledger blade having an opening forming converging cutting edges; a vertically reciprocable movable blade having converging cutting walls normally cooperating with the cutting edges of the ledger blade; means for reciprocating the movable blade including a support for the blade; means for elevating the support to thereby render the movable blade ineffective; means for supporting the ledger blade for lateral movements; a spring connected to the ledger blade for maintaining the latter in yieldable engagement with the movable blade during cutting operations and for moving the ledger blade out of registry with the movable blade when the latter is in its elevated and ineffective position; and a cam finger fixed to the movable blade support and cooperating with the ledger blade to automatically return the latter to its normal position during the return movement of said support.

10. In a combined seaming and pinking machine, the combination of a stitch forming mechanism including a vertically reciprocatory needle, and a trimming mechanism including a horizontally disposed ledger blade having an opening forming converging cutting edges; a vertically reciprocable movable blade having converging cutting walls normally cooperating with the cutting edges of the ledger blade; a lever pivoted on a horizontal axis and carrying the movable blade; means for moving said lever; means for swinging the lever upwardly to thereby render the movable blade ineffective; means for supporting the ledger blade for lateral movements; a spring connected to the ledger blade for maintaining the latter in yieldable engagement with the movable blade during cutting operations and for moving the ledger blade out of registry with the movable blade when the latter is in its elevated and ineffective position; and a cam finger fixed to the lever and cooperating with the ledger blade to automatically return the latter to its normal position during the return movement of the lever.

11. In a combined seaming and pinking machine, the combination of a stitch forming mechanism including a vertically reciprocatory needle, and a trimming mechanism including a horizontally disposed ledger blade having an opening forming converging cutting edges; a vertically reciprocable movable blade having converging cutting walls normally cooperating with the cutting edges of the ledger blade; means for reciprocating the movable blade including a support for the blade; means for elevating the support to thereby render the movable blade ineffective; means for supporting the ledger blade for lateral movements; a spring connected to the ledger blade for maintaining the latter in yieldable engagement with the

- movable blade during cutting operations and for moving the ledger blade out of registry with the movable blade when the latter is in its elevated and ineffective position; a 5 stop to limit the lateral movement of the ledger blade under the influence of the spring when said ledger blade is out of registry with the movable blade, and a cam finger fixed to the movable blade support and having a cam located below the cutting edge of the movable cutter and cooperating with the ledger blade to automatically return the latter to its normal position during the return movement of said support.
- 10 12. In a combined seaming and pinking machine, the combination with a stitch forming mechanism including a rotary shaft and a vertically reciprocating needle; of a trimming mechanism including a vertically reciprocating trimming blade located at one side of the needle and having converging cutting edges, and a ledger blade cooperating therewith; and means operated by the shaft and including a reduction gear coupling for reciprocating the trimming blade concomitantly with certain of the needle reciprocations.
- 15 13. In a combined seaming and trimming machine, the combination with a rotary shaft, of a stitch forming mechanism including a vertically reciprocable needle operated by said shaft, and a trimmer mechanism including a ledger blade and a vertically reciprocable blade cooperating therewith, a vertically movable frame carrying the movable blade, a cam rotated by the main shaft and operatively engaging said frame for vertically moving the latter, means for moving the reciprocating blade and the ledger blade 20 to inoperative positions, and means for restoring the cooperative relation of the reciprocating blade and ledger blade upon return of the reciprocating blade to its operative position.
- 25 14. In a combined seaming and trimming machine, the combination with a rotary shaft, of a stitch forming mechanism including a vertically reciprocable needle operated by said shaft, and a trimmer mechanism including a ledger blade and a vertically reciprocable blade cooperating therewith, a vertically movable frame carrying the movable blade, a cam rotated by the main shaft and operatively engaging said frame for vertically moving the latter, means for moving the reciprocable blade to an inoperative position, means for moving the ledger blade to inoperative position when the reciprocable blade is rendered inoperative, and means 30 movable with the reciprocable blade for restoring cooperative relation of the blades when the reciprocable blade is returned to its operative position.
- 35 15. In a combined seaming and trimming machine, the combination with a rotary shaft, of a stitch forming mechanism including a vertically reciprocable needle operated by said shaft, and a trimmer mechanism including a ledger blade and a vertically reciprocable blade cooperating therewith, a vertically movable frame carrying the movable blade, a cam rotated by the main shaft and operatively engaging said frame for vertically moving the latter, means for moving the reciprocable blade to an inoperative position, means for moving the ledger blade to inoperative position when the reciprocable blade is rendered inoperative, and means 40 movable with the reciprocable blade for restoring cooperative relation of the blades when the reciprocable blade is returned to its operative position.
- 45 16. In a combined seaming and trimming machine, the combination with a rotary shaft, of a stitch forming mechanism including a vertically reciprocable needle operated by said shaft, and a trimmer mechanism including a ledger blade and a vertically reciprocable blade cooperating therewith, a vertically movable frame carrying the movable blade, a cam rotated by the main shaft and operatively engaging said frame for vertically moving the latter, means for silencing the reciprocable blade, and means automatically active upon silencing of the reciprocable blade to displace the ledger blade.
- 50 17. In a combined seaming and trimming machine, the combination with a rotary shaft, of a stitch forming mechanism including a vertically reciprocable needle operated by said shaft, and a trimmer mechanism including a ledger blade and a vertically reciprocable blade cooperating therewith, a vertically movable frame carrying the movable blade, a cam rotated by the main shaft and operatively engaging said frame for vertically moving the latter, means for silencing the reciprocable blade and for returning it 55 again to operative position, and means automatically active upon silencing of the reciprocable blade to displace the ledger blade and upon return of the reciprocable blade to operative position replace the ledger blade in normal cooperative relation with the reciprocable blade.
- 55 18. In a combined seaming and trimming machine, the combination with a rotary shaft, of a stitch forming mechanism including a vertically reciprocable needle operated by said shaft, and a trimmer mechanism including a ledger blade and a vertically reciprocable blade cooperating therewith, a vertically movable pivoted frame carrying the movable blade, means cooperating with one of the blades to bodily move said blade toward the cooperating blade for yieldably holding the blades in shearing engagement during the trimming operation, and a cam rotated by the main shaft and having wiping contact with 60

said frame intermediate the pivotal mounting of the frame and the reciprocable blade for vertically moving the latter.

19. In a combined seaming and trimming machine, the combination with a rotary shaft, of a stitch forming mechanism including a vertically reciprocable needle operated by said shaft, and a trimmer mechanism including a ledger blade and a vertically reciprocable blade cooperating therewith, a vertically movable pivoted frame carrying the movable blade, a cam rotated by the main shaft and having wiping contact with said frame intermediate the pivotal mounting of the frame and the reciprocable blade for vertically moving the latter in one direction, a spring cooperating with one of the blades to bodily move and yieldably hold that blade in shearing relation against the remaining blade during the trimming operation, and a spring for maintaining the frame in operative engagement with said cam.

20. In a combined seaming and trimming machine, the combination with a main frame including a work support, a standard on the work support, and an overhanging arm supported on the standard, of a stitch forming mechanism including a vertically reciprocable needle mounted on the overhanging arm, a rotary shaft journaled in the overhanging arm and having operative connections with said needle, and a trimming mechanism including a ledger blade and a cooperating movable blade, a cam rotatably supported by the overhanging arm, a gear coupling for imparting rotation from the rotary shaft to the cam, a lever carrying the movable blade disposed between the overhanging arm and the work support, and means for pivotally mounting the lever in position for being operatively engaged and moved by said cam.

21. In a combined seaming and trimming machine, the combination with a main frame including a work support, a standard on the work support, and an overhanging arm supported on the standard, of a stitch forming mechanism including a vertically reciprocable needle mounted on the overhanging arm, a rotary shaft journaled in the overhanging arm and having operative connections with the needle, and a trimming mechanism including a ledger blade and a cooperating movable blade, a cam rotatably supported by the overhanging arm, a gear coupling for imparting rotation from the rotary shaft to the cam, a lever carrying the movable blade disposed between the overhanging arm and the work support, and means for pivotally mounting the lever in position for being operatively engaged and moved by said cam, said gear coupling including reduction gearing for causing the blades to cooperatively engage during certain but not all needle strokes.

22. In a combined seaming and trimming

machine, the combination with a main frame including a work support, a standard on the work support, and an overhanging arm supported on the standard, of a stitch forming mechanism including a vertically reciprocable needle mounted on the overhanging arm, a rotary shaft journaled in the overhanging arm and having operative connections with said needle, and a trimming mechanism including a ledger blade and a cooperating movable blade, a cam rotatably supported by the overhanging arm, a gear coupling for imparting rotation from the rotary shaft to the cam, a lever carrying the movable blade disposed between the overhanging arm and the work support, means for pivotally mounting the lever in position for being operatively engaged and moved by said cam, a spring for maintaining the lever in operative engagement with the cam, and means for yieldably holding the blades in shearing relation during operation.

23. In a combined seaming and pinking machine wherein is provided a work support and an overhanging arm, the combination with a stitch forming mechanism including a rotary shaft mounted in the arm and a vertically reciprocating needle, of a trimming mechanism including a vertically reciprocating trimming blade located at one side of the needle and having converging cutting edges and a ledger blade cooperating therewith, a reciprocating frame supported beneath the arm and carrying said trimming blade, means operated by the shaft for moving said frame, and means carried by the frame for rendering effective or ineffective at will said frame moving means.

24. In a combined seaming and pinking machine wherein is provided a work support and an overhanging arm, the combination with a stitch forming mechanism including a rotary shaft mounted in the arm and a vertically reciprocating needle, of a trimming mechanism including a vertically reciprocating trimming blade located at one side of the needle and having converging cutting edges and a ledger blade cooperating therewith, a reciprocating frame supported beneath the arm and carrying said trimming blade, means operated by the shaft and including a reduction gear coupling for moving the frame concomitantly with certain of the needle reciprocations, and means carried by the frame for rendering effective or ineffective at will said frame moving means.

In testimony whereof I affix my signature.
